UNITED STATES PATENT OFFICE.

CLARENCE M. MUFFLY, OF HOWARD, PENNSYLVANIA.

CARRYING AND DISPLAY CASE.

1,163,256.

Specification of Letters Patent.

Patented Dec. 7, 1915.

Application filed March 27, 1915. Serial No. 17,465.

To all whom it may concern:

Be it known that I, CLARENCE M. MUFFLY, a citizen of the United States, residing at Howard, in the county of Center and State of Pennsylvania, have invented certain new and useful Improvements in Carrying and Display Cases, of which the following is a specification, reference being had to the accompanying drawings.

10 This invention comprehends certain new and useful improvements in package and article carriers and relates particularly to an improved carrying and display case for use by carpenters, machinists, electricians, commercial travelers and the like, for transporting their tools or goods from place to place, or for the display of same in a sample room, show window, or the like.

The invention has for its primary object 20 an improved device of this character, the construction of which is such that relatively light and thin materials or substances, such as indurated fiber, may be used for the main part of the case, the device embodying 25 an improved construction of supporting or reinforcing framework, whereby the completed case will be light and yet strong and durable and not liable to become deformed or distorted in any way during service.

30 A further object of the invention is a simple, durable, and efficient construction of carrying and display case wherein the entire case is supported by the reinforcing frame, a part of which is securely connected to the 35 handle by which the device is carried, whereby the weight carried by the handle will not be imposed upon that part of the case to which the handle is directly applied, but will be taken up and sustained by the supporting 40 and reinforcing frame.

The invention has for a still further object to provide a device of this kind in which the supporting framework is made in two main parts, one of which is mounted 45 within the body of the case and the other mounted within, or applied to, the closure or lid, means being provided whereby when the lid is in closed position, these two main parts of the supporting framework will be 50 interlocked, and the lid will be securely supported by the reinforcing framework as well as the body portion itself. And the invention also aims to generally improve devices

of this character so as to render them more useful and commercially desirable.

55 For a full understanding of the invention, reference is to be had to the following description and accompanying drawing, in which,

Figure 1 is a perspective view of one 60 form or embodiment of the invention, with the lid or closure shown in open position, the embodiment illustrated being designed particularly for use by carpenters or hardware salesmen for holding a kit of tools, 65 although it is to be understood that this embodiment is shown for the purposes of illustration only and that my invention is not limited to any particular use or adaptation. Fig. 2 is a transverse sectional view 70 through the case with the parts closed one upon the other.

Corresponding and like parts are referred to in the following description and designated in the views of the accompanying 75 drawing by like reference characters.

Referring to the drawing, the numeral 1 designates the main or body portion of a case embodying the principles and improvements of my invention, and 2 the lid thereof. 80 These parts may be formed of any suitably strong and light material or substance such as indurated fiber or the like, for it is to be understood that the main object of my invention is to produce a case wherein a light 85 and yet strong supporting framework maintains the case in proper shape, notwithstanding that a heavy weight may be carried thereby and that I do not depend upon the material out of which the shell or walls of 90 the body portion and lid of the case are formed to secure the desired rigidity and strength.

Within the body portion of the case is mounted one of the main parts of the supporting and reinforcing framework hereinbefore referred to. In the present instance, this framework comprises longitudinally extending bars 3 and 4 mounted within the body portion near the top and bottom thereof and if desired secured thereto in any way, and transversely extending bars or standards 5 which are disposed at right angles to the bars 3 and 4, and that are preferably mortised, as indicated at 6, to receive said longitudinally extending bars. The upper edges

of the standards 5 (it being understood that the terms "upper" and "lower" are here relatively used and for the purposes of identification only in connection with the accompanying drawing), are formed with recesses 7 designed to receive a main supporting bar 8, which extends longitudinally of the body portion of the case just underneath the top thereof, as clearly illustrated in Fig. 1, the bar 8 being secured to the standards 5 by nails or similar fastening devices.

9 designates the handle whereby the entire device is carried, said handle being formed of leather or any other suitable substance or material. The handle 9 is connected to the main supporting bar 8 by means of U-shaped clips 10 which extend underneath and around said bar and have their extremities passing up through the top 20 of the body portion 1 and riveted or otherwise secured to metallic or similar straps 11 which extend over and across the ends of the handle 9. Thus it will be understood that the handle 9, although applied to the outer 25 wall of the top of the body portion 1 imposes no strain at all thereon, as the handle is directly connected to the main supporting bar 8 underneath the top. It is to be understood that while I prefer the use of the clips 30 10 and straps 11 for securing the handle to the bar 8, my invention is not limited to that construction and arrangement of parts, as the handle may be otherwise connected to the bar 8, within the purview of my invention.

The closure or lid 2 for the case has the other main part of the supporting framework mounted therein and if desired secured thereto in any way. This part also includes 40 longitudinally extending bars 12 and 13 preferably located near the upper and lower edges of the lid and posts or standards 14 extending at right angles to the bars 13 and mortised, as at 15, to receive said bars, just 45 as the standards 5 are mortised. Dowel pins 16 are secured to the relatively inner edges of the standards 14 and project perpendicularly therefrom, said dowels being designed to enter sockets 17 formed in the opposing 50 edges of the posts 5, whereby, as will be clearly understood, when the lid is in its closed position, as clearly illustrated in Fig. 2, the dowels, by being received within the sockets 17, will lock the standards 14 and 55 standards 5 together, and thus the standards 5 will not only be supported from the handle 9 through the instrumentality of the main supporting bar 8, but will in turn support the standards 14, and consequently the entire 60 supporting framework, and the casing or shell within which it is mounted will not only be firmly held in shape and prevented from being deformed or distorted in any way, but will be able to support a very

heavy load without any strain coming upon 65 the walls of the receptacle itself.

As set forth at the outset of the specification, the present embodiment of the invention is designed for use as a kit for tools, and with that in view, the standards 5 and 70 14 have openings formed therethrough for saws, boring bits, and similar tools, although it is to be understood that this is merely a matter of design, as the invention is not limited to this application. Preferably, the 75 relatively inner edges of the standards 14 are cut away or formed with beveled recesses 18 at one end and the opposing edges of the standards 5 are similarly formed with oppositely beveled recesses 19, the walls of the 80 two recesses interengaging and conforming to each other when the parts are in closed position, as illustrated in Fig. 2.

From the foregoing description in connection with the accompanying drawing, it will 85 be seen that I have provided a very simple, durable, and efficient construction of carrying or display case wherein the parts are so arranged that a thin substance or material may be used for the shell or walls of the 90 casing, owing to the fact that the reinforcing framework is strong and rigid and will prevent the walls of the case from becoming distorted while at the same time, the manner in which the handle is connected to the 95 supporting and reinforcing framework will cause all of the weight of the articles received within the case to be imposed upon the supporting framework and entirely relieved from the walls themselves. It is to be 100 particularly noted that the body portion and the lid of the case are cut at their meeting edges on oblique lines terminating in one corner, where the hinges are connected. This allows for a flat opening, as indicated 105 in Fig. 1 of the accompanying drawing.

While the accompanying drawing illustrates what I believe to be the preferred embodiment of my invention, it is to be understood that the invention is not limited thereto, but that various changes may be made in the construction, arrangements and proportions of the parts without departing from the scope of the invention as defined in the 110 appended claim.

What I claim, is:

A case of the character described comprising a body portion, a lid connected thereto, a reinforcing and supporting framework constructed in two main parts, one of which 115 is mounted within the body portion and the other within the lid, one of said parts embodying longitudinally extending bars and standards extending at right angles to the bars and secured thereto, a main supporting bar connected to one set of standards and extending underneath and close to the top of the case, a handle applied to the top of the 120 125

case on the outside thereof, fastening means secured to said main supporting bar and connecting the handle thereto, the other main part of the framework embodying longitudinally extending bars and standards secured thereto, the first named standards being formed in one edge with sockets, and dowels secured to the other set of standards

and receivable in said sockets, as and for the purpose set forth. ¹⁰

In testimony whereof I hereunto affix my signature in the presence of two witnesses.

CLARENCE M. MUFFLY.
